United States Patent Office

Des. 228,371

Patented Sept. 18, 1973

228,371

CHAIR

Don Ray Gill, Sturgis, Mich., assignor to Mohasco
Industries, Inc., Amsterdam, N.Y.

Filed Jan. 26, 1972, Ser. No. 221,126

Term of patent 14 years

Int. Cl. D6—02

U.S. Cl. D6—26

The figure is a perspective view of a chair illustrating my new design.

The back of the chair is conventionally plain while the side not shown is substantially identical to the side shown.

I claim:

The ornamental design for a chair, as shown and described.
